(57) **CLAIM**

The ornamental design for single-lobe bag for infusion products, as shown and described.

DESCRIPTION

FIG. 1 is a perspective view of a first embodiment of a single-lobe bag for infusion products;

FIG. 2 is a front face view thereof;

FIG. 3 is a side view thereof;

FIG. 4 is a rear face view thereof;

FIG. 5 is a bottom plan view thereof;

FIG. 6 is a perspective view of a second embodiment of a single-lobe bag for infusion products;

FIG. 7 is a front face view thereof;

FIG. 8 is a side view thereof;

FIG. 9 is a rear face view thereof; and,

FIG. 10 is a bottom plan view thereof.
